UNITED STATES PATENT OFFICE.

GEORGE C. CONE, OF TOLEDO, OHIO, ASSIGNOR TO OHIO STEEL WHEEL-BARROW COMPANY, OF TOLEDO, OHIO.

WHEELBARROW-FRAME.

SPECIFICATION forming part of Letters Patent No. 758,824, dated May 3, 1904.

Application filed February 20, 1903. Serial No. 144,233. (No model.)

To all whom it may concern:

Be it known that I, GEORGE C. CONE, of Toledo, county of Lucas, and State of Ohio, have invented certain new and useful Improvements 5 in Wheelbarrow-Frames; and I do hereby declare that the following is a full, clear, and exact description of the invention, which will enable others skilled in the art to which it appertains to make and use the same, reference 10 being had to the accompanying drawings, and to the figures of reference marked thereon, which form part of this specification.

My invention has reference to a wheelbarrow-frame, and has for its object to provide a 15 frame which shall be inexpensive and which shall combine maximum strength with minimum weight.

The invention is especially adapted to be employed in the construction of wheelbarrows 20 used largely by masons, contractors, and the like, by whom a wheelbarrow is required which is capable of sustaining a heavy load without danger of collapsing or breaking when lifted by means of the handles.

25 In the well-known construction of wood-frame barrows the leg-supports and the longitudinal bars of the frame are secured together by means of a mortise-joint, the up-standing tongue upon each leg-support being

30 clamped to the bar by means of a transversely-extending bolt. The longitudinal bars are obviously weakened by this construction, and I have found that wood-frame barrows so constructed invariably break at the junction of 35 the leg-supports with the longitudinal bars. To overcome this objection and to provide a frame of great strength and rigidity which shall be insured against collapsing under the the weight of a heavy load, my invention is 40 constructed and the same comprises the novel arrangement hereinafter shown and described, and illustrated in the accompanying drawings, in which—

Figure 1 is a perspective view of my 45 proved wheelbarrow-frame. Fig. 2 is an elevation, partly in section, of one side of the frame, illustrating the construction; and Fig. 3 is a transverse section showing the relative arrangement of the metal and wood portions 50 of the frame.

The frame proper comprises two longitudinal wooden frame-pieces 1, formed with handles 2, and between the forward ends of the same a wheel is adapted to be rotatably mounted.

55 3 represents bars of metal, preferably constructed of steel, L-shaped in cross-section and adapted to be secured to the longitudinal frame-pieces, the webs of each bar lying in close contact with the bottom and one of the side faces of each frame-piece. Each metal bar is bent downwardly at 4 and formed with a return-bend, as at 5, and is again bent angularly at 6. By thus bending the metal bars extremely rigid leg-supports are provided for 60 the frame.

65 7 represents bolts extending vertically through the horizontal web of the L-shaped metal bars and the longitudinal frame-pieces and adapted to clamp them together. By 70 passing the clamping-bolts vertically through the wooden frame-pieces the strength of the latter is not impaired. It is obvious that if said frame-pieces were perforated transversely the same would be weakened and liable to 75 break at the points where the bolts pass therethrough.

80 8 is an L-shaped cross-bar secured between the leg-supports of the metal bars 3.

85 It will be apparent that a wheelbarrow-frame constructed as herein described will be extremely rigid and that the added rigidity provided by the metal bars clamped to the wooden frame-pieces as described will insure maximum strength with minimum weight.

85 Although I have herein referred to L-shaped metal bars adapted to be clamped to the wooden frame-pieces, it is apparent that channel or U-shaped metal bars may also be employed, said U-shaped bars being clamped to embrace 90 the frame-pieces on the bottom and sides, the clamping-bolts being arranged to extend vertically upward through the U-shaped bars and the frame-pieces.

95 Having described my invention, what I claim, and desire to secure by Letters Patent, is—

In a frame for a wheelbarrow of the type set forth, the combination with the pair of members, having handle-forming portions 100

thereon, provided with a series of vertically-disposed bolt-receiving openings therein, a pair of members L-shaped in cross-section and supporting each of said first-named members upon their horizontal lower face, said members having openings therein adapted to register with those of the first-named members, whereby securing means may be vertically received within the same, said members comprising a substantially U-shaped body portion forming legs for the frame, and forwardly and rearwardly projecting members extending substantially at right angles to the body por-

tions the forwardly-extending portions being of greater length than the rearwardly-extending portions and an L-shaped brace member securing the body portions of the said last-named members in fixed position, substantially as set forth. 15

In testimony that I claim the foregoing as my own I affix my signature in presence of two witnesses.

GEORGE C. CONE.
